UNITED STATES PATENT OFFICE.

PAUL F. COX, OF CHICAGO, ILLINOIS.

STENCIL-ADDRESSING MACHINE.

Application filed December 15, 1920. Serial No. 430,963.

To all whom it may concern:

Be it known that I, PAUL F. Cox, a citizen of the United States, residing at Chicago, in the county of Cook and State of Illinois, 5 have invented certain new and useful Improvements in Stencil-Addressing Machines; and I hereby declare that the following is a full, clear, and exact description thereof, reference being had to the accompanying 10 drawings, which form part of this specification.

This invention is a novel mechanism for addressing articles, such as envelopes, packages, newspapers, and the like, by applying 15 to each of such articles the address of the person for whom it is intended.

This invention is an improvement on the type of addressing mechanism shown in my Patent No. 1,344,384, dated June 22, 1920.

20 The particular objects of the invention are to provide novel means for applying the addresses by means of stencils; to provide novel means for taking the stencil plates from the feed chute and releasing them after 25 they have passed the printing point; to provide novel means for holding the stencil on the carrier between the feed chute and the point of discharge; to provide novel magnetic holding means and to provide novel 30 means for inking the stencils.

I will explain the invention with reference to the accompanying drawings which illustrate one embodiment of the invention and will enable others skilled in the art to 35 readily adapt and use the invention; but I do not consider the invention in its broader aspects restricted to the specific construction of the addressing mechanism shown; and therefore I have set forth in the claims the 40 essentials of the invention and novel combinations of parts and novel features of construction for which protection is desired.

In the accompanying drawings:

Figure 1 is a front elevation of my novel 45 addressing mechanism attached to the frame of a printing press in operative relation to the folder former.

Fig. 2 is an enlarged side elevation of such addressing mechanism.

Fig. 3 is a partial front view of Fig. 2 50 partly broken away.

Figure 4 is a detail view of one of the stencils.

Fig. 5 is a transverse section of the stencil on line 5—5 Fig. 4. 55

The operative parts of the addressing mechanism may be mounted in any suitable frame affording proper support therefor. The addressing mechanism is adapted to use individual address stencils. These stencils 60 are usually stamped out of a thin sheet of suitable material and surrounded by a thicker metal frame to stiffen the thin metal strips, the latter bearing the name and address and other indicia of the addressee. 65 Preferably I make the stencil out of suitable preferably non-metallic material such as shown at S, Figures 4 and 5, which sheet is secured in a metal frame S' which permits the stencil to be pressed by a suitable ink 70 pad against the paper—this frame is preferably formed of a plate having side flanges S² turned over and clamping the stencil sheet S as indicated in Figure 5.

One end of the plate has an opening S³ 75 corresponding to a notch in the stencil sheet to facilitate handling the stencil. I do not however consider the invention limited to any particular form of stencil, but prefer to use stencils formed either of magnetizable 80 metal or having a magnetizable metal frame.

These stencils are supplied to the addressing mechanism from a feed chute 2 of any suitable construction supported upon a suitable frame preferably in such manner that 85 the chute may be supplied with stencils without stopping the operation of the machine. The feed chute is provided with suitable slots in its front and rear walls at the bottom thereof so that the stencils can be 90 successively ejected therefrom one at a time.

The stencils may be supported in the chute 2 by means of fingers 2² at the lower end of the chute 2 and preferably formed in or attached to a plate 2¹ supported on the frame, the lowermost stencil resting on the fingers 2² in position to be removed from the galley 95 by devices on a rotating stencil carrier 4.

As shown the carrier 4 is a cylindrical drum attached to a shaft 4^b, which may be operated as described in my aforesaid patent. Said carrier is provided with pairs of opposed stencil-grippers 5 and 6. The grippers 5 are mounted on a rock shaft 5^a which is journaled in bearings in the carrier 4 (see Figs. 2 and 3), one gripper 5 at each side of the drum, which is slotted to permit the grippers to be set inside of the ends of the drum, so that they will pass by the stencil supporting fingers 2^e. The shaft 5^a has an arm 5^b on one end carrying a roller 5^c which rests upon a cam 5^d fastened to one part 8 of the supporting frame in which part the outer end of the shaft 4^b is journaled (see Fig. 3).

The grippers 6 are attached to a shaft 6^a journaled in the carrier 4 opposite shaft 5^a, and shaft 6^a has an arm 6^b which carries a roller 6^c engaging a cam 6^d fast to the part 8. These cams 5^d, 6^d are so proportioned and arranged that at the proper time in the rotation of the carrier the grippers 5 and 6 will be caused to close upon the lowermost stencils in the chute 2 and withdraw the same therefrom and carry same around to and past the printing point P. After the stencil has passed the printing point the grippers 6 are retracted out of the way in time to allow the forward edge of the stencil to drop upon a guide 7 and beneath the upper end of a stripping guide or finger 7^a parallel with the guide 7 (Fig. 1), and the discharged stencils pass between the guides 7 and 7^a, and are directed thereby into a receiving galley 7^b into which they are stacked by any suitable means.

As shown a pusher 7^e is provided mounted on a rock shaft 7^f having an arm 7^g connected by a rod 7^h to a crank arm 4^e attached to the outer end of the shaft 4^b (see Figs. 1 and 3) so that the pusher will be oscillated at the proper time to move each stencil discharged from the carrier forward in the chute 7^b.

The shafts 5^a, 6^a are rocked at the proper time to prevent the grippers 5 and 6 contacting with the stripping fingers or guides 7 or 7^a and then returned to operative position. The cams are so arranged that the grippers will be opened before they reach the chute 2 and will be closed upon the lowermost stencil in the chute in time to take the same from the chute 2 and carry same to the printing point.

Slidably mounted upon the carrier are stencil holding magnets 9, which are preferably permanent U-shaped magnets and are arranged with their poles intermediate the grippers 5 and 6 (see Fig. 2), there being one magnet 9 at each side of the carrier and guided in grooves therein. These magnets may be reciprocated diametrically of the carrier 4 and at the proper time by any suitable means.

As shown the opposed magnets may be connected by transverse bars or rods 9^y and 9^x so that they move together; and the rod 9^x is engaged with an arm 9^a attached to a rock shaft 9^b journaled in and extending through the carrier 4 (Figs. 2 and 3), said rock shaft having a crank arm 9^e having a roller 9^c on its outer extremity contacting with a cam 9^d concentric to the shaft 4^b and fastened to the fixed part of the main frame 1, in which the inner end of the shaft 4^b is journaled. The shaft 9^b may be rocked in opposition to the cam by means of a suitable spring.

As shown the guide slots for the magnets in the carrier are preferably provided with brass bushings 9^z so as to insulate the magnets from the metal of the frame and adjacent parts, so that the power of the magnets may be most effective at the poles thereof, and engage and retain the stencil or stencil holders on the carrier.

These magnets are adapted to engage and hold the stencil on the carrier by magnetic attraction, being projected so that their poles will engage with the iron frame of the stencil when and as the stencil is being ejected from the chute 2 by the grippers 5, and these magnets will hold the stencil close to the periphery of the carrier during the printing operation, but are retracted at proper times so that the stencil will be dislodged and discharged by and between fingers 7, 7^a, as described.

When the parts are properly designed these magnets will hold the stencil firmly while the stencil is being inked and while it is making an impression, and then they are retracted to release the stencil and remain retracted until another stencil is taken from the finger 2^e.

As shown the carrier 4 has an opening in its periphery intermediate the opposed grippers and opposite magnets (see Fig. 3) and within the carrier opposite this opening is arranged a reciprocatory inking pad 10, which pad may be connected with the magnets 9 so as to be raised and lowered therewith.

As shown in Figures 2 and 3 the ink pad 10 is carried by a member 10^a which is slidably guided in suitable opening in the carrier 4 and preferably has centrally disposed lugs 10^b which rest upon the arms 9^a so that the ink pad is reciprocated simultaneously with the magnets 9. Preferably the ink pad may be normally retracted by means of a spring 10^c attached to the member 10^a and the hub of the carrier as shown in Figures 2 and 3. This spring will normally hold the ink pad and the magnets in retracted position when the cam 9^d permits.

In the construction shown the ink pad will be inked before the stencil and magnet reach the chute 2. The ink pad may be sup-

plied with ink by any suitable means. As conventionally shown in Fig. 1 the ink pad receives ink from a roller 11, which is supplied with ink by distributing rollers 11^a, 5 11^b, to which the ink is supplied by a ductor 11^c from a fountain 11^d, which may be conveniently attached to the support (see Fig. 1). This ink supplying means may be of any other suitable construction.

10 When the stencil reaches the printing point P ink is projected on to the paper through the perforations in the stencil. If desired, any suitable means may be provided for preventing the stencils sliding off the 15 carrier because of the action of centrifugal force. Either the magnets, or the grippers 5 and 6, would ordinarily prevent this, but as an additional precaution a curved retainer plate or bar 5ⁿ may be arranged between the stencil taking point and the printing and discharge point as indicated in Fig. 20 1 to effectively prevent the stencils becoming displaced by centrifugal force.

After the impression is made the stencils 25 are carried by the member 4 to the point of discharge and released by any suitable means, as described.

A receiving galley (not shown) can be 30 detachably attached to the outer end of the receiving chute 7^b in the usual manner to receive the stencil discharged from the galley 7^b.

The apparatus shown is especially adapted for use in connection with printing 35 presses, and preferably the supporting frame 1 is so constructed that it can be readily attached to the folded former F of a printing press, as in my aforesaid patent. As shown in Fig. 1 R is the usual roller 40 mounted on the shaft S^s at the top of the former F and rotated to assist the web of paper W to and over the former. The shaft S^s is driven by gearing (not shown), and above said shaft is a tie rod T, which usually carries spring pressed rollers which 45 hold the web W in contact with the roller R at the top of the former. Below the shaft S^s is a bar B which supports the upper end of the former F. The addressing attachment frame 1 is shown as connected with and supported by the rods T and bar B as described in my aforesaid patent.

When applied to a printing mechanism 50 the parts should be so driven and the gearing so proportioned that the stencils on the carrier will be moving at the printing point at the same speed as the paper or article to be impressed, passing such point.

In the example shown, the shaft 4^b carries a gear 4ⁿ which meshes with a gear 4° attached to and driven by the shaft S^s; and the gears 4ⁿ and 4° are so proportioned that the stencil carrier will be rotated once for each newspaper, or impression on the paper 65 when applied to a printing press, and the

parts are preferably adjusted so that the address will be printed upon the margin of each newspaper as it passes over the former.

While I have described the invention as embodied in an attachment for web printing presses and applied to such presses it will be obvious to those skilled in the art that the invention could be readily embodied in a separate machine for addressing envelopes, packages and the like. In such cases the supporting frame would be properly modified, and means provided for rotating the shaft 4^b manually or by power, as will be readily understood and provided by those familiar with the art.

It should also be understood that while the invention is described as especially adapted for use in addressing mechanisms, the magnetic means for holding the objects such as stencil plates on the carrier, could be readily adapted to other carriers and for holding other kind of address or printing plates or other objects on a carrier. Therefore I do not consider the magnetic holding means limited to use in connection with addressing mechanism or magnetizable stencils or printing plates.

What I claim is:

1. In stencil addressing mechanism the combination with a magnetizable stencil member; a movable carrier; and permanent magnets thereon adapted to retain the magnetizable stencil member thereon, and cam means for causing the magnets to take the stencils at the receiving point, and to release the stencils after the printing operation.

2. In stencil addressing mechanism, the combination with magnetizable stencil members; a rotatable carrier; magnets thereon adapted to retain the magnetizable stencils thereon; means for operating the carrier; and means for causing the magnets to take the stencils at the receiving point and to release the stencils after the printing operation.

3. In combination with mechanism as set forth in claim 2; means within the carrier for applying ink through the stencil at the printing point, substantially as described.

4. In combination a movable rotatable stencil carrier; permanent magnets for holding the stencil on the carrier; means for feeding magnetizable stencils to the carrier; and cam means for causing the magnets to engage the stencil at the taking point and to discharge the stencil after the printing operation.

5. In combination with mechanism as set forth in claim 4; means within the carrier for applying ink to the stencil at the printing point, substantially as described.

6. In combination a movable rotatable stencil carrier; magnetic stencil holding means on the carrier; means for supplying magnetizable stencils; means for causing the

magnets to engage a stencil; and means for causing the magnets to discharge the stencil after the printing operation; and means within the carrier for supplying ink through the stencils at the printing point.

7. In an addressing apparatus, means for supplying individual stencils; a carrier provided with grippers adapted to take the stencils successively from the supply and carry them past the point of impression; permanent magnet means on said carrier for holding the stencils; and means for causing the grippers to release the stencil after the printing operation; and means for receiving the discharged stencils.

8. In combination with mechanism as set forth in claim 7; means within the carrier for applying ink through the stencils at the printing point, substantially as described.

9. In combination, a rotatable member adapted to carry a printing stencil; a feed chute for supplying stencils to said member; means on said member for taking a stencil from the feed chute; permanent magnet means on said member for holding the stencil until the impression has been made; cam means for causing said permanent magnet means to release the stencil after the impression; and means for discharging the stencil after printing.

10. In combination with mechanism as set forth in claim 9; means within the carrier for applying ink through the stencils at the printing point, substantially as described.

11. In an apparatus of the character specified, a feed chute for printing stencils having bottom supports for the stencils; a rotatable carrier below the chute having means adapted to remove a stencil from the chute; permanent magnet means on said carrier for holding the stencil during the printing operation; cam means for causing the holding means to release the stencil after printing; and means for discharging the stencils after printing.

12. In combination with mechanism as set forth in claim 11; means within the carrier for applying ink through the stencil at the printing point, substantially as described.

13. In an addressing apparatus, means for supplying individual stencils; a carrier adapted to take the stencils successively from the supply and carry them past the point of impression; means on said carrier for holding the stencils; means for applying ink through the stencils at the printing point; and means for discharging the stencil from the carrier after the printing.

14. In an addressing apparatus, means for supporting individual stencils; a carrier adapted to take the stencils successively from the supply and carry them past the point of impression, grippers on said carrier for holding the stencils; means for discharging the stencil from the carrier after the

printing operation; means for receiving the discharged stencils; and means within the carrier for applying ink through the stencil at the printing point, substantially as described.

15. In combination, a rotatable member adapted to carry a printing stencil; a feed chute for supplying stencils to said member; grippers on said member for taking a stencil from the feed chute and for holding the stencil until the impression has been made; and means for causing said grippers to release the stencil after the impression.

16. In combination with mechanism as set forth in claim 15; means within the carrier for applying ink through the stencil at the printing point.

17. In an apparatus of the character specified, a feed chute for printing stencils having bottom supports for the stencils; a rotatable carrier below the chute having devices on its periphery adapted to remove a stencil from the chute; grippers on said carrier for holding the stencil during the printing operation; means for causing the grippers to release the stencil after printing; a receiving galley for released stencils; and means for packing the stencils in the galley.

18. In apparatus as set forth in claim 17; a rotatable carrier and a radially movable inking member within the carrier adapted to supply ink through the stencils at the printing point.

19. In an addressing apparatus, means for supplying individual stencils; a carrier adapted to take the stencils successively from the supply and carry them past the point of impression; opposed sets of grippers on said carrier for holding the stencils; means for applying ink through the stencils at the printing point; means for discharging the stencils after the printing operation; and means for receiving the discharged stencils.

20. In mechanism as set forth in claim 19; a reciprocatory inking member within the carrier and operating between the grippers and adapted to supply ink to the paper through the stencil at the printing point; and means for operating said inking member.

21. In an addressing apparatus; a carrier for stencils; an inking member in the carrier; and means for causing said member to apply ink through the stencil at the printing point.

22. In an addressing apparatus; means for supplying individual stencils; a carrier adapted to take stencils from the supply and past the point of impression; an inking member in the carrier; means for causing said member to apply ink through the stencil at the printing point; and means for discharging the stencil after the printing operation.

23. In apparatus as set forth in claim 22;

a rotatable carrier and a radially movable inking member within the carrier, substantially as described.

24. In addressing apparatus; means for supplying stencils; a rotatable carrier adapted to take the stencils successively from the supply and carry them past the printing point; oppositely disposed pairs of grippers mounted on said carrier; and means 10 for causing the said grippers to engage the

stencils at the taking point and release same after it has passed the printing point.

25. In mechanism as set forth in claim 24; an inking member in the carrier adapted to supply ink to the paper through the stencil 15 at the printing point; and means for operating said inking member.

In testimony that I claim the foregoing as my own, I affix my signature.

PAUL F. COX.
